MANTLE PROTECTOR

Emil G. Koebnick, Stewart, Minn.

Application May 17, 1932. Serial No. 611,901

4 Claims. (Cl. 240—102)

This invention relates to lamps generally. More specifically this invention relates to fuel lamps employing fragile mantles.

An object of this invention is to provide a protector over the mantle of a fuel fed lamp in such a manner that the mantle and protector may be attached to the lamp as a unit and shield the mantle from objects tending to come in contact therewith.

10 Still another object of this invention is to provide a unit to lamps employing mantles adapted to fit over the lamp mantle and be attached as a unit therewith for shielding the mantle from objects tending to come in contact therewith.

15 A further object of this invention is to provide a mantle protector for gas lamps such that the protector may be slipped directly over the mantle at a spaced distance therefrom and attached to the fuel feed pipe.

20 Other and further objects of this invention will be apparent to those skilled in the art to which it pertains from the following specification and the appended claims.

In accordance with this invention a screen, 25 which may be of a coarseness of mesh varying from a fine to a relatively coarse mesh, is shaped into an elongated pouch and provided with an annular member or an adjustable clamp member at the open end for attachment to the fuel feed pipe of a gas mantle type of lamp.

30 This screen is displaced from the outer surface of the mantle a slight distance depending upon the coarseness of the mesh thereof so that the minimum of shadow will be cast by it in the light transmitted from the mantle.

35 In a modified form of this invention the screen is attached to the mantle support and retained in position thereby.

40 A more detailed impression of this invention may be obtained from the specification when read in conjunction with the drawing wherein

45 Fig. 1 of the drawing illustrates a vertical fragmentary sectional view of the construction of an embodiment of this invention; Fig. 2 shows a modified form of this invention; Figs. 3 and 4 illustrate detail views of the fastener used for retaining the mantle protector in position over the mantle; Fig. 5 shows a modified form of this invention employing a screw adjusted fastener;

50 Fig. 6 is a sectional view in side elevation of still another modified form of this invention. Fig. 7 is a top view of the form of this invention illustrated in Fig. 6; Fig. 8 shows an enlarged detail view of the fastener used in the modified form 55 of this invention illustrated in Figs. 6 and 7. Fig.

9 shows in partial section still another form of this invention, and Fig. 10 illustrates an alternative form of fastener used in accordance with this invention.

In Fig. 1 of the drawing reference numeral 1 designates a screen formed into an elongated pouch shaped member, fitting over the gas mantle 2. The screen 1 and the mantle 2 are supported by the member 3, which is of refractory material and which is provided with a centrally positioned hole to receive the fuel feeding tube 4. A thin wire 5 covered with asbestos is cemented to the mantle 2 at the upper extremity thereof for retaining the mantle upon the member 3.

Suitable refractory compositions which harden upon heating, such as thoria, or magnesia mixed to form a cream with materials such as glue, or water glass, may be used to cement the mantle 2 to the member 3 and retain the asbestos covered wire 5 in position. A thin wire member 6 is provided to the open end of the screen 1 to cooperate with this screen and the member 3 in retaining the screen in position over the mantle. If desired, this screen may be slipped completely over the member 3 and engage the tube 4 as illustrated in Fig. 9 of the drawing. The member 6 is preferably attached to the screen at one or two points by a spot welding, however, this is not necessary as the wire member 6 may be threaded through the screen in one or more places and the relative positions thus retained.

In Fig. 2 is illustrated a form of the screen 1 before it is positioned over the mantle 2. While this screen is illustrated as having a seam 1a, it is of course, understood that by properly spinning a pouch shape member from a certain section of screening the seam may be eliminated. In positioning the member 1 over the mantle the wire 6,

which is provided with a loop 7 at one end thereof and a loop 8 at the other end thereof is adjusted so that a kink 9 formed adjacent to the loop 8 engages the section 10 adjacent to the loop 7 and thus partially closes the opening of the screen 1 as illustrated in Fig. 1. The wire 6 may be made of any suitable materials such as iron or copper and is preferably made so as to maintain slight resiliency. The relative positions of the different loops in the wire member 6 are more clearly illustrated in Fig. 3.

In Fig. 4 a slightly modified form of the fastening arrangement adapted for use with the wire 6a corresponding to the wire 6 of Fig. 3, is illustrated. In this case the wire 6a is provided with loops 11 and 12 at the extremities thereof, which are adapted for engagement when

it is desired to control the opening formed in the screen pouch.

Where it is desired to receive more positive fitting of the screen over the top 4 the form of this invention illustrated in Fig. 5 is preferable. A band 13 having holes formed in the extremities thereof to receive the screw 14 is applied to the screen pouch 1. In use the screw 14 is tightened until the band 13 causes the open end of the pouch to engage the tube 4 and retain the pouch in position.

In Figs. 6, 7 and 8 another modified form of this invention is illustrated in which the screen 15 is retained in position upon the flange 16 of the supporting member 20. Pipe 18 is attached to the section 19 for feeding fuel through the hole formed in the member 20 to the gas mantle 21. The mantle 21 is retained in position upon the member 20 by the asbestos thread 22.

20 The screen 15 is retained in place by the member 17, illustrated in Figs. 6, 7 and 8, which is made of a piece of wire or iron, copper, brass or the like, distorted out of shape in such a manner that the sections 17a engage the upper surface 25 of the flange as illustrated in Figs. 6 and 7, and the sections 17b engage the lower peripheral surface. In applying this member 17 it is preferred to have the screen attached to it and to spring the sections 17a over the edge of the flange 20. In 30 this case it is desirable to make the member of resilient material such as is not readily affected by temperatures developed by the lamp.

Another form of this invention is illustrated in Fig. 9 of the drawing wherein the screen protecting member 23 is supported direct on the fuel pipe 25 by the wire 24. The wire 24 may be threaded through the screen in several places or it may be attached thereto by spot welding. In order to facilitate attachment of the screen to the 40 member 26 when the mantle 27 is larger than the pipe 25, a section of the screen is cut away adjacent to the opening, as illustrated in Figs. 2 and 5 of the drawing; this permits expansion of the mouth of the screen pouch so that the screen may 45 be placed over the mantle and the mantle sup-

porting member. After the screen is in position the mouth thereof is contracted by the wire 24 which is illustrated slightly enlarged in Fig. 10, is either twisted together or fastened in any of the different ways illustrated.

80 While I have described several modified forms of my invention in considerable detail, it is of course, understood that I do not desire to limit it specifically in detail to any one of the particular screens except in so far as is defined by the 85 appended claims.

What I claim and desire to secure by Letters Patent of the United States is as follows:

1. In gas mantle protectors the combination 90 of a gas mantle, means for supporting said mantle, a pouch shaped screen and means including a band shaped member having ends thereof adjustably attached together for supporting said pouch shaped screen over said gas mantle.

2. In gas mantle protectors the combination 95 of a gas mantle, means for supporting said mantle, a pouch shaped screen positioned over said mantle; a band shaped member attached to said pouch shaped screen for supporting said screen over said mantle, and means attached adjacent 100 to the ends of said band shaped member for adjusting said band shaped member so that said screen may be readily attached or removed.

3. In gas mantle protectors the combination 105 of a gas mantle, means for supporting said mantle, a screen protector surrounding said mantle and means for supporting said screen protector including an elongated member having means positioned on the ends thereof for detachably supporting said screen protector in place.

4. In a gas mantle protector the combination 110 of a gas mantle, means for supporting said mantle, a screen pouch-shaped protector having an open end and surrounding said mantle, means for supporting said screen including a band and 115 means for retaining the ends of said band in engagement and for contracting the open end of said screen about said mantle supporting means.
